UNITED STATES PATENT OFFICE.

CLIFFORD J. PUGH, OF SALEM, OREGON.

EXHAUST BOX AND COOKER.

Application filed November 20, 1922. Serial No. 602,080.

To all whom it may concern:

Be it known that I, CLIFFORD J. PUGH, a citizen of the United States, residing at Salem, in the county of Marion and State of Oregon, have invented certain new and useful Improvements in Exhaust Boxes and Cookers, of which the following is a specification, reference being had to the accompanying drawings.

10 This invention relates to certain improvements in exhaust boxes and cookers and has relation more particularly to a device of this general character especially designed and adapted for use in connection with the 15 canning industry for the purpose of pre-heating fruit or the like before the operation of sealing the cans.

It is an object of the invention to provide 20 a novel and improved device of this general character embodying a box provided with heating means together with a conveyor travelling through said boxes wherein means is provided for the requisite delivery 25 of cans or the like upon the conveyor for travel through the box and means for conveying said cans or the like out of the box.

Another object of the invention is to provide 30 a novel and improved device of this general character embodying a conveyor travelling through the box together with means for carrying the cans or the like within the box and wherein additional means are automatically operated at predetermined 35 intervals to cause the cans or the like admitted within the box to pass upon the conveyor for travel through the box.

The invention consists in the details of 40 construction and in the combination and arrangement of the several parts of my improved exhaust box whereby certain important advantages are attained and the device rendered simpler, less expensive and otherwise more convenient and advantageous for use, as will be hereinafter more fully set forth.

45 The novel features of my invention will hereinafter be definitely claimed.

In order that my invention may be the 50 better understood, I will now proceed to describe the same with reference to the accompanying drawings, wherein:

55 Figure 1 is a view in side elevation with portions broken away of an exhaust box constructed in accordance with an embodiment of my invention;

Figure 2 is a fragmentary view in eleva-

tion taken at the discharge end of the box and at the side opposite to that illustrated in Figure 1;

Figure 3 is a fragmentary view in plan 60 of the conveyor or apron travelling through the box;

Figure 4 is an enlarged fragmentary view partly in plan and partly in section of the mechanism arranged at the receiving end 65 of the box;

Figure 5 is a fragmentary view in side elevation of the structure illustrated in Figure 4;

Figure 6 is a view partly in section and 70 partly in elevation of the mechanism for operating a plunger as comprised in the present invention;

Figure 7 is a fragmentary view in perspective of the structure illustrated in Figure 6 together with additional mechanisms 75 associated therewith.

Figure 8 is a fragmentary view in elevation illustrating in detail the driving means 80 for the disks;

Figure 9 is a fragmentary sectional view 85 of the structure at the delivery end of the box;

Figure 10 is a fragmentary view partly in top plan and partly in section of the delivery end of the structure;

Figure 11 is a fragmentary view in perspective clearly illustrating the screen element arranged within the box; and

Figure 12 is a view in cross section of the 90 structure as illustrated in Figure 11.

As disclosed in the accompanying drawings, B denotes a box or housing of predetermined dimensions and which is supported at a desired elevation by the legs 1 arranged 95 at the opposite ends of the device.

Travelling along and within the lower portion of the box B is the upper stretch 100 of an endless conveyor C travelling in the direction as indicated by the arrow a in Figure 1 of the drawings. This conveyor C passes around the drums 2 and 3 positioned adjacent the opposite ends of the box and provided with the shafts 4 rotatably supported by the bearings 5 carried by the supporting legs 1. The upper stretch of the conveyor C has contact with the idler rollers 6 arranged below said upper stretch whereby the portion of the conveyor C within the box is caused to move in substantially a fixed path of travel and without sagging. The lower portion of the con-

veyor C, as is illustrated particularly in Figure 1, passes over the tension roller 7.

The conveyor C comprises the side or marginal chains 8 connected by the cross rods 10 and interposed between adjacent rods 10 and engaged therewith are the links 11. This construction of the conveyor C provides an open fabric for a purpose to be hereinafter more particularly referred to.

10 The side chains 8 of the conveyor C engage the sprockets 12 carried by the opposite ends of the drums 2 and 3. The shaft 4 of the drum 2 is extended and has fixed thereto a worm gear 14 with which is engaged a worm 15 carried by the shaft 16. The shaft 16 extends longitudinally of the box B and is supported by the adjacent legs 1. The shaft 16 is also provided with means, such as a pulley 17, for driving the 20 same, said pulley being herein disclosed as positioned adjacent to the delivery or discharge end of the box B.

The shaft 16 is in driving connection as at 18 with a transversely disposed shaft 19 of a length to extend beyond the opposite side of the box B. The opposite end portion of the shaft 19 is in driving connection as at 20 with a roller 21, said roller 21 being disposed transversely of the box 20 and positioned between the upper portion of the drum 2 and the discharge or delivery runway 22 within the box, said runway 22 leading to a delivery opening 23 provided at one side wall of the box B. The roller 21 is rotated in a direction to facilitate the passage from the upper stretch of the conveyor C to the runway 22 of the cans or containers carried by the upper stretch of the conveyor. The cans or other containers received upon the runway 22 are caused to pass outwardly through the opening 23 through the instrumentality of the endless chain 24 arranged edgewise and travelling along the runway 22 and passing outwardly 40 through the opening 23.

A stretch of the chain 24 passes through a center slot of the runway 22 to assure the proper functioning of the chain 24. The chain 24 is disposed around the sprockets 25 supported at opposite sides of the box B, the sprocket 25 at the side of the box provided with the delivery opening 23 being carried by a vertically disposed shaft 26 in driven connection as at 27 with the shaft 19 hereinbefore referred to, said connection 27 being herein shown as a co-acting worm and worm wheel.

The runway 22 may extend a suitable distance beyond the box B and the cans or 60 the containers disposed on said extended portion of the runway are adapted to be delivered to a suitable sealing mechanism.

A side wall of the box B adjacent the end thereof remote from the runway 22 is 65 provided with an entrance opening 28 with

which is associated a runway 29, said runway extending transversely through the box B and having an extended portion 30, the outer longitudinal marginal portions of the extended portion 30 of the runway being 70 provided with outstanding guide flanges 31.

The runway 29 and the extended portion 30 are provided at substantially their transverse centers with a slot 32 through which traverses a stretch of an endless chain 33. 75 This chain 33 is disposed edgewise and is directed around the sprocket wheels 34 and 35 positioned adjacent the opposite end portions of the runway.

The sprocket 34 is carried by a vertically disposed shaft 36 rotatably supported by an outboard bearing 37 while the sprocket 35 is rotatably supported by an upstanding bearing 38 carried by the adjacent side of the box B. The second or outer stretch of 85 the chain 33 remains exteriorly of the box B and passes inwardly over the idler sprockets 39 supported by the bearings 40 carried by the rear portion of the box B. The chain 33 between the idlers 39 is engaged with the sprocket wheel 41 keyed to a vertically disposed shaft 42. The shaft 42 is rotatably supported by the bearings 43 extending rearwardly from the receiving end of the box B. 95

The lower portion of the shaft 42 is in driven connection by the chain 44 or the like with a second vertically disposed stub shaft 45 supported by suitably arranged bearing 46. The shaft 45 is in driven connection as at 47 with the shaft 16 as is believed to be clearly illustrated in Figures 1, 4 and 5 of the accompanying drawings. The shaft 42 extends above the sprocket 41 and loosely mounted for rotation upon said extended portion 43 is a disk D provided in its peripheral portion with a radially disposed open slot a. Extending within the slot a and pivotally engaged therein as at 48 is an end portion 105 of a clutch arm 47 which when in its lowered position engages between adjacent upstanding lugs 48 carried by the peripheral portion of the sprocket 41 outwardly of the disk D whereby the disk D will be 110 caused to rotate in unison with the sprocket 41. While the arm 47 may drop by gravity I find it of advantage to constantly urge said arm downwardly through the instrumentality of the spring b having one 115 end portion secured as at 49 to the disk D while the opposite or free end portion of said spring 48 contacts from above with the arm 47. 120

The arm 47 is of a length to extend beyond the periphery of the sprocket 41 when in its lowered position, said extended portion of the arm 47 being adapted to engage and ride upwardly upon the cam block 50. The cam block 50 has its high 125

point so arranged as to raise the arm 47 sufficiently to free the same from lugs 48 so that the sprocket wheel 41 may rotate independently of the disk D.

- 5 As the arm 47 rides up the cam block 50 and when it reaches the high point of said cam 50 said arm contacts with an outstanding stop member 51 carried by the adjacent end portion of the box B whereby the disk 10 D is positively held against rotation with the sprocket 41 until the arm 47 has been permitted to drop between a pair of adjacent lugs 48.

The cam block 50 is carried by the upper 15 end portion of a vertically disposed rock arm 52 carried by a suitably supported bracket 53. The pivoted portion of the arm 52 is continued by an extension 54 terminating in an outwardly directed arm 55, 20 said arm 55 extending below the chain 33 and intersecting the path of travel of a trip member 56 carried by and suitably positioned upon the chain 33.

When the member 56 contacts with the 25 arm 55 the continued travel of the chain 33 will result in swinging movement of the arm 52 to an extent sufficient to cause the cam block 50 to entirely pass from below the arm 47 whereupon said arm 47 will 30 be free to drop for clutch or locking engagement with the sprocket 41. The rear wall of the box B immediately adjacent the runway 29 is provided with a slot 57 extending substantially entirely across the 35 box B and through which is adapted to pass a plunger or push bar 58, said plunger or bar 58 being herein disclosed as constituting an angle iron. Rigidly secured as at 59 to one end portion of the plunger 40 or bar is a pitman 60 which is operatively engaged with the upstanding wrist pin 61 carried by the disk D.

The opposite end portion of the plunger or bar 58 has pivotally engaged therewith, 45 as at 62, a rigid link 63 the opposite end of said link being pivotally engaged as at 64 with an outstanding arm 65 carried by the rear portion of the box B. During the period the disk D rotates the plunger or 50 push bar 58 will be caused to pass across the runway 29 and in a manner to force from said runway 29 upon the adjacent portion of the upper stretch of the conveyor C the cans or containers which have 55 been carried within the box B through the instrumentality of the chain 33 and as indicated by dotted lines in Figure 4.

The cans or other containers are placed upon the extension 30 of the runway 29 60 after leaving the filling machine and as said cans or containers pass or travel through the box B the contents of said cans are preheated and preferably by action of steam. One or more steam pipes 66 are 65 arranged within the box B and extend longi-

tudinally thereof at a point below or in close proximity to the upper stretch of the conveyor C, said pipe or pipes directing upwardly jets of steam, the construction of the conveyor readily permitting said steam 70 to pass therethrough so that an effective preheating of the contents of the cans or containers within the box B will be assured.

The device is also adapted to be employed 75 as a cooker and when so employed the screen 67 is arranged within the box B and through which the conveyor C is directed as is clearly illustrated in the accompanying drawings, said screen having depending side walls 68 terminating in the flanges 69 disposed on a downward and inward incline. The side walls 68 are imperforate while the top wall of the screen 67 is provided with minute openings 70. 80

The screen 67 when applied extends substantially the entire length of the box B and has its side walls 68 spaced from the side walls of the box B with the top of the screen also spaced from the top of the 90 box B. When the screen 67 is applied and the device adapted to be used as a cooker, the bottom of the box has a supply of water placed therein the level of which terminating above the pipes 66 and preferably about two inches. As is illustrated in Figures 11 and 12 it is to be noted that the side pipes 66 are arranged outwardly of the screen 67 and between the side walls 68 of the screen and the adjacent side walls 95 of the box. The steam discharging from the side pipes 66 and the water brought to a boiling point the force of velocity of the steam discharged from these pipes will force the water up the sides 67 and over and 100 across the top of the screen 67 resulting in a hot water spray over the cans as they pass 105 through on the conveyor C.

Certain of the pipes 66 underlie the conveyor C and serve mainly for heating the 110 water although the jets discharged from these last named pipes result in a slight raising of the adjacent portion of the water to meet the spray that is delivered downwardly from the screen. The flanges 115 69 provide means to facilitate the creation of the requisite suction to carry the water upwardly of the sides 68 of the screen 67. In order that the water may be properly arranged within the box I provide said 120 box with transversely disposed walls 71 positioned adjacent the receiving and delivery runways.

From the foregoing description it is thought to be obvious that an exhaust box 125 constructed in accordance with my invention is particularly well adapted for use by reason of the convenience and facility with which it may be assembled and operated, and it will also be obvious that my inven- 130

tion is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:—

10. An apparatus for preheating cans of fruit or the like before sealing the cans comprising, in combination, an exhaust box, a conveyor travelling therethrough, a runway extending within the box adjacent to an end 15 of the conveyor and transversely of said conveyor, a member disposed transversely of the conveyor and outwardly of the runway, said member being movable transverse-

ly of the runway, a rotatable member positioned adjacent to the box, and beams operatively engaged with one end portion of the member and with the rotatable member, an outstanding arm carried by the box adjacent the opposite end of the member, a rigid link pivotally engaged with the outer 25 end portion of said arm and the member, and means for rotating the rotary member, such rotation of the rotary member intermittently moving the first named member across the runway, the movement of said first named member across the runway in one direction forcing the cans upon the runway within the box upon the conveyor. In testimony whereof I hereunto affix my signature.

CLIFFORD J. PUGH.
